UNITED STATES PATENT OFFICE.

JOHN J. CASE, OF SARATOGA SPRINGS, NEW YORK, ASSIGNOR OF ONE-HALF TO JOHN J. WRIGHT, OF SARATOGA SPRINGS, NEW YORK.

THROTTLE REGULATOR.

1,404,009.

Specification of Letters Patent. Patented Jan. 17, 1922.

Application filed April 7, 1920. Serial No. 372,023.

To all whom it may concern:

Be it known that I, JOHN J. CASE, a citizen of the United States, residing at Saratoga Springs, in the county of Saratoga and State of New York, have invented an Improvement in Throttle Regulators, of which the following is a specification.

This invention relates to a throttle regulator and while its use is not so limited, it is particularly designed for use in conjunction with internal combustion engines and employed in motor cars as an accelerator auxiliary to control the carbureter throttle and consequently the admission of fuel to the manifold and engine in order to obtain a substantially uniform development and application of the power of the engine. As will be readily understood, in the ordinary form of accelerator operated by the foot of the driver, the fuel is admitted with great irregularity, causing corresponding irregularity in the development and application of the power, the disadvantages of which are overcome by the use of the device made in accordance with my present invention. My improved throttle regulator preferably comprises a casing or body member in which a plunger or its equivalent is mounted to reciprocate or move and the movement thereof controlled by the passage of a suitable liquid from one chamber to another in the casing, the flow of the liquid from one chamber to another being caused by a movement in one direction of the plunger and the return of the liquid permitted by a movement of the plunger in the opposite direction, the plunger being connected to an accelerator rod in any suitable manner so as to make any too rapid movements of the accelerator and consequently the throttle of the carbureter impossible either in opening the throttle or closing the same as will be hereinafter more particularly described.

In the drawing:

Fig. 1 is a central longitudinal cross section and partial elevation illustrating the throttle regulator made in accordance with my invention.

Fig. 2 is a cross section on line 2—2, Fig. 50 1, and

Fig. 3 is a diagrammatic chart illustrating the differences in the development and application of the power in the employment of the throttle regulator herein shown and described, and without the same as at present is common practice.

Referring to the drawing, the throttle regulator made in accordance with this invention preferably comprises a casing or body member 10 which may be cylindrical or of any other configuration, and made of a suitable metal or any other material. At one end, this casing is provided with a flange 11 and fitted with a cover 12 which is secured to the flange of the casing by the use of bolts 13 as illustrated, or otherwise. In the casing 10, as illustrated, there are two compartments, the one indicated at 14 and the other at 15, these compartments being separated by a partition wall 16 in which there is a vent 17 making a communication between the said compartments. This vent is preferably fitted with a valve 17' operated exteriorly of the casing in order to regulate the area of the vent and thus control the rate of flow of the liquid through the same in passing from either compartment to the other.

Associated with the casing there is a plunger 18. This plunger 18 passes through a hole 19 provided therefor in the cover 12 and also through bearings 20 in the partition wall 16, the plunger fitting in the said bearing and being adapted to be moved therein into and out of its normal position as indicated in Fig. 1. In order to maintain the plunger 18 in this initial or normal position, I prefer to employ a spring 22 which extends between the inner end of the plunger and the base of the compartment 15 in which a recess is provided for the reception of the inner end of the spring to maintain the same in position. In the compartment 15 I also prefer to employ a quantity of mercury 23 or other similar and suitable fluid material which, when the parts are in their normal position, substantially fills this compartment 15 as shown in the drawing.

The upper or outer end of the plunger is preferably fitted or provided with a head 24 in which there is a slot 25 to receive a trunnion or other attachment 26 carried by a lever or rod 27 connected to the accelerator and the throttle of the carbureter in any suitable manner, the connection between the lever 27 and the plunger being a flexible joint as will be readily understood.

In the operation of the throttle regulator as hereinbefore described, and as will now be apparent in operating the lever to control the throttle either in one direction or the other that is to open and close the same,

the development and application of the power will be substantially constant and rapid variations of the same are made impossible. For example, and by reference to Fig. 3, it will be seen that when the parts of the apparatus are set to depress the plunger in opening the throttle the movement of the same will be retarded by making it necessary first to depress the plunger causing the flow of the mercury from the compartment 15 to the vent 17 to the compartment 14, and the usual effect of vibrations, due to the travel over rough roads, and of rapid changes, due to starting and stopping, will be overcome, and that when the power is shut off the change is also gradual because the closing of the throttle is controlled by the return flow of the mercury through the vent 17 from the compartment 14 to the compartment 15, the plunger being normally forced upwardly and maintained in its initial or normal position by the use of the spring 22 as hereinbefore described.

I claim as my invention:

1. In an apparatus of the class described, a body having separate compartments therein, in one of which there is contained a liquid, a plunger passing through one compartment and into the other compartment, there being a passage for the liquid from the liquid compartment to the other compartment through which the liquid is caused to pass when displaced by the plunger entering the liquid compartment, and a tension device acting in conjunction with the plunger to normally maintain the same in an initial position in which the liquid employed substantially fills the liquid compartment and none of the liquid is contained in the other compartment.

2. In an apparatus of the class described, a body having a transverse wall dividing the same into compartments, in one of which there is contained a liquid, a plunger passing through one of the said compartments and through the said transverse wall in which it is journalized in a bearing provided therein for the same, and a tension device acting in conjunction with the said plunger to normally maintain the same in an initial position, there being a passage between the said compartments for the flow of the liquid from the liquid compartment to the other compartment when displaced by the plunger entering the liquid compartment against the action of the said tension device.

3. In an apparatus of the class described, a body having a transverse wall therein dividing the same into compartments, one of which is substantially filled with liquid, a plunger journalized in the said transverse wall and extending into the liquid compartment, there being a passage in the transverse wall through which the liquid is caused to flow

from the liquid compartment when displaced by the plunger entering the same, and a tension device coacting with the said plunger to normally maintain the same in an initial position in which the liquid compartment is substantially filled with the liquid.

4. In an apparatus of the class described, a body having a transverse wall therein dividing the same into compartments, one of which is substantially filled with liquid, a plunger journaled in the said transverse wall and extending into the liquid compartment, there being a passage in the transverse wall through which the liquid is caused to flow from the liquid compartment when displaced by the plunger entering the same, a tension device coacting with the said plunger to normally maintain the same in an initial position in which the liquid compartment is substantially filled with the liquid, and means for regulating the flow of the liquid through the said passage.

5. In an apparatus of the class described, a body having a transverse wall dividing the same into inner and outer compartments, a plunger passing through the outer compartment and through a bearing therefor in the said transverse wall and normally a slight distance into the inner compartment which is substantially filled with a liquid, there being a passage extending through the transverse wall for the flow of the liquid from the inner to the outer compartment when displaced by the plunger entering the inner compartment, and a spring extending between the inner end of the said plunger and the oppositely disposed wall of the inner compartment for normally maintaining the plunger in an initial position.

6. In an apparatus of the class described, a body having a transverse wall dividing the same into inner and outer compartments, a plunger passing through the outer compartment and through a bearing therefor in the said transverse wall and normally a slight distance into the inner compartment which is substantially filled with a liquid, there being a passage extending through the transverse wall for the flow of the liquid from the inner to the outer compartment when displaced by the plunger entering the inner compartment, a spring extending between the inner end of the said plunger and the oppositely disposed wall of the inner compartment for normally maintaining the plunger in an initial position, and a valve for regulating the flow of the liquid through the said passage from one compartment to the other.

Signed by me this 26th day of March, 1920.

JOHN J. CASE.
